SPINNING FRAME CREEEL

Louis M. Cotchett, Hingham, Mass., assignor to
Saco-Lowell Shops, Boston, Mass., a corpora-
tion of Maine

Application July 16, 1941, Serial No. 402,581

5 Claims. (Cl. 242—131)

This invention relates to spinning frames, more especially of the type used in cotton spinning, and it has for its general object to effect economies in the manufacture and use of machines of this type.

Important objects of the invention are to reduce the floor space required by a spinning frame to the end of reducing the overhead expense involved in the spinning operation, and to facilitate the servicing which any spinning frame requires, especially that involved in replacing empty roving bobbins, piecing up, and similar operations.

An analysis of the labor costs in a cotton spinning room shows that a surprisingly high proportion of such costs are for cleaning. In some mills this proportion will run as high as forty percent of the entire operating cost. Cleaning is important primarily from the standpoint of quality of the product manufactured. Or, to state the matter differently, if the spinning frames are not kept clean of lint and fly a noticeable drop in quality occurs. This fact is well known in the industry and it is the controlling reason for the expenditure of so much time and pains in keeping the machines clean.

Accordingly, a further important object of this invention is to devise a spinning frame which, in a very substantial measure, will keep itself clean.

The nature of the invention will be readily understood from the following description when read in connection with the accompanying drawings, and the novel features will be particularly pointed out in the appended claims.

In the drawings,

Figure 1 is a plan view of a portion of a spinning frame constructed in accordance with this invention;

Fig. 2 is a side elevation of the machine shown in Fig. 1;

Fig. 3 is a vertical, sectional view approxi-
mately on the line 3—3, Fig. 1;

Fig. 4 is a horizontal section, the plane of sec-
tion being taken just above the bobbin whorls;

Fig. 5 is a perspective view of a portion of a spinning frame at the tail end of the machine showing a preferred method of enclosing the mechanism in the machine base;

Fig. 6 is a view, partly in side elevation and partly in vertical section, showing a detail of construction of the creel;

Fig. 7 is a horizontal, sectional view, partly in elevation, showing another detail of the creel structure;

Fig. 8 is a side view of the construction shown in Fig. 7; and

Fig. 9 is a vertical, sectional view approxi-
mately on the line 9—9, Fig. 8.

Referring first to Figs. 2 and 3, a spinning frame is there shown of a type disclosed in an earlier application of mine. This machine comprises sectional units secured end to end, each unit being substantially a complete spinning machine except for a driving mechanism. As illustrated, each section includes two lines of spindles 2 mounted at opposite sides of the frame, each spindle being adapted to support a bobbin, and all the spindles being driven by bands or tapes which, in turn, are driven from a central cylinder 3, Fig. 3. Cooperating with the respective lines of spindles are the usual rings mounted on ring rails 4—4, thread bores 5—5, and two rows of sets of drawing rolls 6—6 which draw strands of roving from the supply bobbins and feed them laterally to the two lines of spindles.

So far as this general arrangement of the parts or mechanisms mentioned is concerned, the machine is essentially like those already known.

In prior art constructions it has been the universal practice to mount a creel for supporting the supply bobbins between the lines of drawing rolls at opposite sides of the frame. Usually the creel board is positioned on and between the roller beams on which the roll stands are mounted, and the lowest lines, rows or tiers of roving bobbins are about on a level with the drawing rolls. Above these lower tiers there usually are one or more additional tiers of bobbins. Such an arrangement necessarily increases the width of the frame by a distance equal to the width of the creel. Usually the first story of the creel stand is designed to accommodate four longitudinal rows of bobbins, and if double roving is to be run, then the creel must include a second story accomodating four more rows of bobbins. With this arrangement it is not easy for an operator of average height and reach to replace an empty bobbin with a full one and to piece up. One of the objects of this invention, therefore, is to devise novel spinning frame and creel structures which will facilitate these operations.

It will be seen from an inspection of Fig. 3 that in the spinning frame provided by this invention the creel is positioned wholly above the machine, the lower story of roving bobbins B consisting simply of two rows or tiers mounted directly over their respective rows of drawing rolls 6 and spaced from them only by a distance suf-

ficient for convenience in piecing up and performing the servicing operations.

Attention is particularly directed to the fact that this re-arrangement permits a reduction in the width of the frame to about half that of the present commercial constructions, due chiefly to the removal of the creel from between the two rows of drawing roll sets, the positioning of these rolls back to back, and the reduction of the space between them to a distance less than the normal diameter of a full roving bobbin, or, in other words, to a distance less than the overall lateral width of either of said rows of drawing roll sets, as will be evident from an inspection of Fig. 3. Also, by mounting the creel substantially as shown, the lower ends of the lowermost bobbins may be positioned below the shoulder level of a person of average height so that all of the bobbins in the creel then are within convenient reach. Moreover, since the bobbins are above or directly over the drawing rolls instead of behind them, an operator standing at either side of the machine is within easy reaching distance of all of the bobbins for that side.

The creel structure itself is of skeleton construction as best shown in Figs. 1 to 3 and 6 to 9, inclusive. Since this particular machine is made up of sectional units located end to end, the creel structure also is preferably made in the same manner. That for the extreme left-hand section shown in Figs. 1 and 2, which in this instance is at the head end of the frame, comprises two upright posts 7 and 8 mounted at opposite ends of the section and a horizontal bar 10 supported on them. Extending through this bar are several cross bars, two of which are relatively short and are shown at 11, the others, indicated at 12, being considerably longer. One of the latter bars is better shown in Fig. 6.

It should be observed that all of the bobbins B in the lower story are suspended from their upper ends, and that all of the bobbins B' in the two central tiers of the upper story are supported in standing positions from their lower ends only. In order to support the bobbins in these positions, all of the cross bars 11 and 12 are equipped with fittings or fixtures like that shown at 13 in Fig. 6. Each of these fittings includes a body 14 having a hole therethrough to accommodate the bar 12, the fitting being set-screwed or otherwise secured to the bar. Secured rigidly to, or integral with, this fitting is a depending stud 15 provided at its lower end with a head providing a ball race and a bushing 16 rests on the balls in said race. An inverted cap 17, provided with a long sleeve-like extension telescoped on to the bushing 16, is secured rigidly thereto and this cap carries two plungers 18-18 sliding in a transverse bore formed in the cap. They are urged apart by a spring 20, the ends of the bore being so contracted as to prevent the plungers from coming out. The bobbin B is composed of roving wound on the wooden bobbin tube b, the bore of which is enlarged at a short distance from its end, and the ends of the plungers 18-18 fit into this enlargement and support the bobbin yieldingly in a suspended position. It can be removed from the fixture merely by a downward pull.

In order to support the upper bobbins B', the fixture body 14 is provided with an integral post 21 having a tapered bearing point at its upper end rotatably supporting a cap 22. This cap encloses substantially the entire post and that part of the fixture above the bar 12, it is shouldered as shown at c to support the bobbin tube b, and

it is spaced from the cylindrical portion of the post by a bearing sleeve 23 made of Oilit or other suitable material. A screw 24 threaded through the skirt of the cap 22 is provided with a cylindrical end to run in a groove d of the fixture and thus to prevent the cap from being lifted off the fixture when the bobbin is removed from it.

Fittings or fixtures of this character support all of the bobbins above referred to, but in addition to them there are two more tiers of bobbins in the second story, indicated at B², which are positioned on the same level as the inner tiers of bobbins in the upper story but are spaced outwardly away from them. These bobbins B² are mounted in standing positions on fittings 25, Fig. 6, like those shown at 13 except that they are made to fit over the ends of the bars 11 or 12 and they include only the parts 21 to 24, inclusive, required to support bobbins in their standing positions.

Associated with the cross bars are upper and lower horizontal guide rails 26 and 27, respectively, which are supported on four upright bars 28. The latter bars themselves pass through and are set-screwed to certain of the cross bars 12, and the rails are drilled vertically to receive the ends of the bars 28, the parts being secured together by screws. At the points where a guide rail of one section adjoins that of another, a sleeve 30, Fig. 1, is provided to receive the abutting ends of the two rails.

While the elements of this creel may be secured together in various ways, a convenient method of attachment of the central bar 10 to the end posts 7 and 8 consists in milling slots, such as those indicated at 31, Fig. 8, in the ends of each bar and securing in these slots the ends of a strap or straps encircling one of the posts. The straps 32, Figs. 7, 8 and 9, cooperate to encircle the posts 8 and are clamped thereon by screws 33, while the projecting ends of these straps are positioned in the slots 31-31 and are secured therein by set screws 34-34. Each set screw is threaded vertically into a tapped hole forming an enlargement of the slot and it is provided with a pointed end which enters between the lower edges of the end portions of the straps and exerts a spreading action on them. At the end post 7 a single strap, shown at 35 in Fig. 1, encircles the post and its ends are secured to the bar 10 in the same manner as are the ends of the straps 32 shown in Figs. 7 and 8.

The arrangement of bobbins illustrated in Figs. 1, 2 and 3 is designed for double roving; that is, two strands of roving are led from separate supply bobbins in the creel to each spindle, the creel supporting sixteen bobbins on each side to supply the eight spindles of a given section. Since all of the bobbins are supported at convenient heights, and because the outermost tiers of bobbins are interrupted, as best shown in Fig. 1, all are located within easy reach. The most difficulty naturally occurs with the central tiers of bobbins B' in the upper story, but the four bobbins B² in the outermost tiers are so spaced that any such difficulty is avoided. They are arranged in pairs and a bobbin space is left empty between each two adjacent pairs, thus providing easy access to three of the bobbins B' in the middle portion of the inner and upper tier. Access to the end bobbins B² is readily obtainable at one end or the other of the outermost tier.

Thus this invention provides a novel creel structure in which the replacement of empty bobbins by full ones and the piecing up operations are

more easily performed than in any of the prior art arrangements of which applicant has been able to learn. The creel is of approximately the same overall width as the maximum width of the spinning frame so that it does not detract from the narrow frame advantage of this machine.

It should also be observed that the bars and rods which form the structural elements of the creel are all made from stock of circular cross-section so that they present no flat horizontal surfaces on which lint and fly can lodge. On the contrary, these surfaces are so curved or sloped that they naturally shed material of this nature and the creel therefore keeps itself clean at practically all times. Thus the labor of cleaning the creel is substantially eliminated.

I have found that the labor of cleaning may further be reduced very materially by covering the space between the lines of spindles with some kind of a smooth surfaced plate such as that shown at 36 in Figs. 3, 4 and 5. Preferably, also, the entire base of the machine is enclosed by side plates 37 and additional plates, such as shown at 38 or 39, where required at an end of the frame. Each of the side plates 37 includes a supplemental plate 37' of approximately L-section secured to its respective plates 37 by a piano type hinge so that it may be swung outwardly to expose the whorls when desired. The margins of the top plate 36 rest on the inner margins of the curved plates 37', the three sets of plates being notched, as shown at 40 in Fig. 5, to fit around the spindles. Normally the plate 36 is held in its operative position by pins or screws so that they may be quickly taken out to permit its removal whenever desired. The abutting edges of adjoining side plates may be covered by strips such as those shown at 41.

With a construction of this nature I have found that the lint and fly which naturally tends to settle down between the lines of spindles is prevented from actually coming to rest in this space by the air currents created by the rotary motion of the bobbins and spindles. In Fig. 4 the arrows indicate, in a general way, what I believe to be the paths taken by these currents of air. There is a down draft from overhead through and around the drawing rolls and the thread boards which naturally tends to carry lint into the space between the rows of spindles, but the whole body of air in said space is in motion and the air currents have ample velocity to prevent the lint from depositing on the smooth upper surface of the plate 36 which, while adapted to catch it, is not allowed to do so. Contributing to this result is the fact that the frame is exceptionally narrow due to the removal of the creel from between the two rows or lines of drawing rolls into a position above them and the whole space from the creel to the plate 36 is open sufficiently for the down flow of air which will carry with it particles of lint and fly substantially as fast as they are shed by the bobbins and the strands passing through the drawing rolls. The air currents relied upon to keep the plate 36 clean are the result of centrifugal action due to the rotative motion of the bobbins. They apparently throw air away from the frame at opposite sides and thus draw air from overhead down through the space between the rows of spindles. Naturally these air currents are more effective in a narrow space than they would be in a wide one.

Since the creel and the cover plate 36 remain clean indefinitely, due to the causes above described, the greater part of the necessity for clean-

ing this frame is eliminated and the labor involved is correspondingly reduced.

In addition to contributing to the object of maintaining the frame clean, as above described, the narrow frame also has the very important advantage of occupying only about half the floor space that is required by the spinning frames now in common use. Every square foot of space in a mill translates itself into a certain fraction of the overhead cost of the product manufactured by that mill. Consequently, such a saving in floor space as that just mentioned is a substantial practical advantage. A further advantage of the creel structure is the fact that it can be manufactured very economically.

While I have herein shown and described a preferred embodiment of my invention, it will be evident that the invention is susceptible of embodiment in other forms without departing from the spirit or scope thereof. For example, it may be desirable in some creels to support all of the roving bobbins from below or to suspend all of them from above, or to make various combinations of these means of support which may differ from the arrangement above shown and described, while still embodying novel features of the invention.

The so-called "clean frame" features above described are not claimed in this application but are claimed in a divisional application Ser. No. 508,673, filed November 2, 1943. Also, the thread board construction per se is not here claimed but is described, illustrated and claimed in a divisional application Ser. No. 549,740, filed August 16, 1944.

Having thus described my invention, what I desire to claim as new is:

1. A creel structure for spinning frames comprising a supporting frame and fittings thereon serving to support two central lower rows only of roving bobbins closely adjacent to each other and at opposite sides of the middle longitudinal plane of the creel, in substantially free positions so that unimpeded access is afforded to them from opposite sides of the creel, said creel having parts serving to support two upper central rows of bobbins above said lower rows and similarly located with reference to said plane, said creel also including means for supporting additional upper rows of bobbins spaced outwardly from said central upper rows, the supports for certain of the bobbins in said outermost rows being spaced farther apart than those in the central rows so as to afford free access to all of the bobbins in said upper central rows.

2. A creel structure for spinning frames comprising posts at opposite ends thereof, bars extending longitudinally of the creel and additional bars extending transversely thereof, said bars being connected with each other and with said posts so that they are all supported by the posts, and fittings carried by said bars and serving to support roving bobbins arranged in two central lower parallel rows closely adjacent to each other and two upper central rows also positioned closely adjacent to each other and two additional rows spaced outwardly from each other and from said upper central rows but located at a level above that of the lower rows, the bobbins in said outer upper rows being so spaced as to afford free access to all of the bobbins in said upper central rows, said fittings being adapted to support the lower bobbins which they carry in suspended positions with their lower ends free and to support the upper bobbins with their upper ends free.

3. A creel structure according to preceding claim 1, in which said supporting frame comprises interconnected horizontal bars all supported in approximately a common horizontal plane, and certain of said fittings are mounted on said bars for supporting said two central lower rows of roving bobbins suspended in running positions below said bars, and other fittings are mounted on said bars for supporting other bobbins by their lower ends only in standing positions above the 10 bars.

4. A creel structure according to preceding claim 1, in which said frame includes horizontal bars and certain of said fittings are mounted on said bars to support the bobbins in running posi- 15

tions above the bars, each of said fittings including a post and a cap rotatably mounted on said post and shouldered to engage the lower end of a bobbin and support it in a standing position.

5. A creel structure according to preceding claim 1, in which said frame includes horizontal bars and certain of said fittings are mounted on said bars to support the bobbins in running positions, each fitting including a post for engaging the lower end of a bobbin to support it in a standing position and a hanger for engaging the upper end of another bobbin and supporting it in a suspended position.

LOUIS M. COTCHETT.
